UNITED STATES PATENT OFFICE.

ANKER S. LYHNE, OF BRIDGEPORT, CONNECTICUT.

VANITY BOX.

Application filed November 7, 1922. Serial No. 599,493.

To all whom it may concern:

Be it known that I, ANKER S. LYHNE, a citizen of the United States, residing at Bridgeport, county of Fairfield, State of Connecticut, have invented an Improvement in Vanity Boxes, of which the following is a specification.

This invention relates to vanity boxes and has for an object to provide a box of this type which will be neat and attractive in appearance, light weight, convenient to use, and will require a small space only in a lady's handbag or pocketbook.

It is a further object of the invention to provide a vanity box adapted to carry compacts of two different kinds of powder with a separate puff for each compact, and will carry them in distinct and separate compartments, so that there will be no mixing of the different kinds of powder.

It is a still further object of the invention to provide a combination puff and powder compact receptacle.

With the foregoing and other objects in view, I have devised the construction illustrated in the accompanying drawing, in which—

Fig. 1 is a side elevation of the box closed.

Fig. 2 is a front elevation thereof, showing the box opened.

Fig. 3 is a central transverse section taken at right angles to Fig. 2, showing the box opened.

Fig. 4 is a transverse section through one form of combined puff and rouge receptacle on an enlarged scale.

Fig. 5 is a similar view showing a slightly different method of securing the puff to the receptacle.

Fig. 6 is a similar view showing a still different means of securing the puff to the receptacle; and

Fig. 7 is a top plan view of a puff adapted for use in the rouge receptacle.

The box shown comprises two cup shaped sections preferably made of thin sheet metal and finished in any desired manner with or without decoration on the outer walls thereof. In the showing in the drawing the thickness of the various walls is somewhat exaggerated. The two sections of the box comprise the body section 10 and the cover section 11 preferably hinged together by a hinge 12, the sections of this hinge being secured to the sections of the box by any suitable means, but preferably by lugs 13

passing through openings in the side walls and bent over on the inner side as is common. The upper side of the side wall of the lower section 10 is rolled to provide a flange 14 of somewhat smaller diameter than that of the body of the section so that it is adapted to telescope within the cover section 11 and also to provide a shoulder 15 to form a top for the edge of the cover section and give a smooth, continuous and neat appearance to the outer walls of the box when the two sections are closed together. The two sections are secured in closed position by a suitable catch such as an outwardly projecting lug 10' adapted to project into a slot 11' cut in the cover section, the two sections being sufficiently resilient to allow ready engagement and disengagement of these elements.

Otherwise the lower or body section is preferably plain and is adapted to have secured to the bottom thereof by any suitable means, such as cement, a powder compact which comprises usually a metal plate 16 upon the upper wall of which moistened powder is allowed to harden providing a cake of powder secured to the plate, as shown at 17. This powder is ordinarily the usual white powder carried in this type of box.

It is very often desirable, however, to carry another kind of powder especially one which has coloring matter, such as rouge, mixed with it, and as the user is often somewhat sensitive about carrying this type of powder it is desirable to have it enclosed in a sealed container which will not open when the box is opened for use of the ordinary white powder. To provide for this, I enclose within the cover and body sections a closed container for the colored powder or rouge, and a puff for use therewith, this container also providing a holder or handle for a puff for use with the white powder, this article being a combination puff and powder receptacle.

Referring to Fig. 4 where the construction of this receptacle is shown in detail, it comprises a lower member 18 provided with an upturned circumferential flange 19. This flange may also be inclined inwardly somewhat. Coacting with this member to form a receptacle, also preferably of sheet metal, is an upper member 20 and shaped substantially as shown with a downwardly extending flange 21 adapted for telescoping

engagement with flange 19, and having an upper portion 22 of less diameter forming a flange or bead 23 adapted to be gripped by the user to facilitate holding of the receptacle and use of the puff carried on the exterior of this receptacle. This puff is shown at 24 and it may be of any desired material such as a body cloth 25 carrying the usual nap, and covers the bottom surface of the lower member 18. It may be secured thereto by various means, but I prefer to extend it up over the top of flange 19 and clamp it between the two flanges 19 and 21 whereby it is securely held in position. The upper member 20 is provided with an opening 26 in the top thereof which is closed by a cover 27 hinged at 28 and is held in closed position by a downwardly projecting lug 29 arranged to engage the forward edge of this opening. This will securely hold the cover in closed position, but will yield to allow easy opening of the cover to allow access to the receptacle by insertion of a finger nail under an upwardly bent portion 30 of cover. Secured in this receptacle by any suitable means such as cement, is the rouge compact 31 and above this a second puff 32, which may be the ordinary cloth puff having a ribbon handle 32' for use in connection with this compact.

It will be obvious from an inspection of Figs. 2 and 3 that the arrangement is very compact. When the cover 11 is raised the combination puff and rouge receptacle remains closed and by merely gripping the flange or bead 23 which forms a convenient holding means, the puff 24 may be used for the application of the white powder without in any way disturbing the rouge compact or having anything to do with the same. Should it, however, be desired to use the rouge compact all that is necessary is to raise the cover 27 when the rouge puff 32 will be easily accessible. It will also be apparent that the two compacts are in entirely different compartments and so are separated at all times and there is no liability of their mixing. Furthermore, by the peculiar arrangement employed the first operation of opening the box gives access to the white powder only and if it is desired to use the rouge powder the second cover 27 must be opened. This eliminates the very undesirable feature of some boxes provided with two kinds of powder in which the act of opening the main box may give access to either one, so that the user never knows in advance to which powder the box will open.

Within the cover section 11 is mounted the usual mirror 33 secured therein by a thin metal ring 34 having a forced fit with the interior of the cover.

In Figs. 5 and 6 I have shown two slightly different ways of securing the puff 24 to the rouge receptacle. The metal parts of

the receptacle are the same as shown in Fig. 4, but instead of clamping the puff between the flanges 19 and 21 I may form a loop 35 about the edge thereof and insert therein an elastic 36 which will hold the puff in position. This renders the puff easily removable from and applied to the holder to allow easy renewal should it become soiled. Instead of the elastic I may employ a draw tape or ribbon 37 as shown in Fig. 6 for holding the puff to the receptacle.

Having thus set forth the nature of my invention, what I claim is:

1. A vanity box comprising cover and body sections, a receptacle enclosed by said sections forming a powder compartment, a puff in said compartment for use with said powder, said receptacle comprising telescoping sections, a powder puff on the exterior of one of said sections and secured thereto by clamping between the sections, the other section being shaped to form a handle to facilitate use of said puff, and a cover carried by the latter section to allow access to said compartment. 90

2. A vanity box comprising cover and body sections adapted to carry a powder compact, a receptacle enclosed by said sections forming a powder compartment, a puff in said compartment for use with said powder, a second puff secured on the exterior of said receptacle and adapted for use with the first mentioned compact, said receptacle being provided with an outwardly extending flange adapted to be gripped to facilitate use of said puff, and a cover for said receptacle to allow access thereto. 95

3. A combination puff and receptacle comprising a rigid receptacle forming a powder compartment, a puff in said compartment for use with said powder, means allowing access to said compartment, and a second puff mounted on the exterior of said receptacle, said receptacle being provided with an outwardly extending flange 100 providing means adapted to be gripped to facilitate use of said latter puff. 110

4. A receptacle forming a powder compartment, a puff in said compartment for use with said powder, said receptacle comprising two metallic sections, one of which has an upwardly and inwardly extending flange adapted to receive the other section, a puff on the exterior of the first section 115 extending over said flange and clamped between said flange and the second section, said second section being provided with means for holding the receptacle to facilitate use of said latter puff, said second section being provided with an opening to allow access to said compartment, and a cover for said opening. 120

In testimony whereof I affix my signature.

ANKER S. LYHNE.
